UNITED STATES PATENT OFFICE

HORACE E. WHITNEY, OF CAMBRIDGE, MASSACHUSETTS, ASSIGNOR TO DOVER STAMPING AND MANUFACTURING COMPANY, OF CAMBRIDGE, MASSACHUSETTS, A CORPORATION OF MASSACHUSETTS

MEASURING AND DISPENSING CAN

Application filed March 27, 1931. Serial No. 525,671.

The invention relates to an improvement in measuring and dispensing cans essentially of the type for dispensing oil.

The object of the invention is to provide a dust-proof can, and one from which the oil will not spill as it is poured from the can. In attaining these objects it is my further object to provide a can having a hinged cover permanently secured to the can and automatically retained in a closed position, and which on opening for the purpose of filling the can may be moved into a convenient out-of-the-way position where it will not add to the bulk of the can, and may conveniently be retained in such position; also, to provide a convenient means for opening the cover.

The invention can best be seen and understood by reference to the drawings, in which—

20 Figure 1 is a view of the can partly in side elevation and partly in vertical section.

Fig. 2 is a side elevation of the top portion of the can.

Fig. 3 is a plan of the top of the can.

25 Fig. 4 shows the can mainly in vertical section and fitted with mechanism for opening the cover which is shown open.

Fig. 5 is like Fig. 4 except that the cover is closed, and

30 Fig. 6 is a plan of the can as shown in Fig. 4.

Referring to the drawings:—

1 represents the body of the can and 2 its handle.

35 Upstanding from the front half of the top of the can is a rounding hood 3 from which projects a funnel 4. The hood presents a rear edge 5 and that portion of the hood bounded by this edge has preferably a slight forward inclination. Upstanding from the rear half of the top of the can is a rim 6 which connects not only with the top of the can body but with the hood at either side thereof. 7 represents the top edge of the rim

40 and the rim is preferably made somewhat deeper at the back than at the front where it joins the hood so that its top edge 7 will have a slight downward and forward inclination.

50 The back of the hood, or that portion

bounded by its rear edge 5, is closed by a plate 9 down to the point where the rim 6 connects with the hood. The bottom edge of this plate is provided with hinge members 10 retaining a hinge-pin or pintle 11 lying in the juncture between the rear edge 5 of the hood and the top edge 7 of the rim. Turning upon this hinge-pin is a cover 12 fitting over the rim with closure against the top edge 7 thereof. The cover is secured to the hinge-pin by hinge members 13 on the fore edge of the cover. The cover is preferably provided with a flanged edge 14.

The cover is automatically held in a normally closed position by means of a coiled spring 15 arranged upon the hinge-pin with one end 16 of the spring bearing against the cover and the other end 17 of the spring bearing against the plate 9 on the hood.

On opening the cover it will open into a position adjacent the rear end of the hood lying substantially parallel with the plate 9. There the cover may be retained against the tension of the spring 15 by means of a spring clip 18 on the top of the hood. This clip is preferably so made that it will become tensioned in an amount sufficient for it to engage and hold the cover in an open position on moving the cover to such position, and the retention of the cover by the clip is facilitated by the flanged edge 14 on the cover.

Thus constructed a substantially dust-proof can is obtained. Oil will not spill when poured from the can even though the can be so carelessly held that the oil will fill the entire top of the can for when the oil is poured from the can the cover provides a bearing for the thumb of the pourer and consequently the cover will be held tightly closed even though the tension of the spring 15 be insufficient to maintain such closure. Accordingly oil will not escape from beneath the cover or crevices at the point of the hinge connection between the cover and the plate 8 for the reason that air entering the body of the can through these crevices will prevent it, and oil will only escape through the funnel.

When open the cover will have been moved

to a position where it will lie snugly adjacent a permanent part of the can and accordingly will not add to the bulk of the can. It will also be moved to an open position 5 where it can conveniently be held in such position either manually by one grasping the hood and cover, or automatically by means of the spring clip as explained above.

A further advantage of the construction is 10 obtained by reason of the fact that the entire top structure is reinforced and this especially by the plate 9 on the rear of the hood, thereby enabling the can to withstand much rough usage.

15 In Fig. 4 the can is shown provided with mechanism by which the cover of the can may be opened and held in an open position. To this end the handle 2' of the can has arranged within it a movable finger grip 20 in the form of a lever. This grip is pivoted at its lower end at the point 21 to the bottom bar 22 of the handle so that the grip may be movable forward and back substantially within the plane of the handle. The upper 20 end of the grip is disposed to lie within the top bar 23 of the handle acting as a guide therefor as the grip is moved forward and back as aforesaid. Connected to the upper end of the grip or lever is a link 24 which 25 extends forward to flexibly connect with the end of a link 25 fastened to the under side of the cover with projection forward beyond the front edge of the cover and beyond the pivotal connection between the cover and the 30 plate 9. With the mechanism thus provided the cover may be opened by one grasping the handle and grip 20 simply by drawing back the grip whereupon the cover will be moved to an open position with bearing 35 against the rear side of the hood acting as a stop therefor substantially as shown in Fig. 4. For holding the grip in a normal forward projected position and for assisting also in holding the cover closed the finger grip is provided with a spring 26 attached to it and curved to have bearing 40 against the interior side of the handle.

Having thus fully described my invention, I claim and desire to secure by Letters Patent 50 of the United States:—

1. A can of the type specified comprising the body of the can, a hood with funnel projection upstanding from the top front of the can body, a top rim to the can body lying back 55 of said hood, a plate closing the back of said hood downward to the point of the top of said rim, a cover to the can body closing against said rim, and means for hinging the cover to said plate.

60 2. A can of the type specified comprising the body of the can, a hood with funnel projection upstanding from the top front of the can body, a top rim to the can body lying back of said hood, a plate closing the back 65 of said hood downward to the point of the top

of said rim, a cover to the can body closing against said rim, means for hinging the cover to said plate, and means for holding the cover in a normally closed position.

3. A can of the type specified comprising 70 the body of the can, a hood with funnel projection upstanding from the top front of the can body, a top rim to the can body lying back of said hood, a plate closing the back of said hood downward to the point of the top of said 75 rim, a cover to the can body closing against said rim, means for hinging the cover to said plate including a hinge-pin lying at the junction between the forward end of the cover and the bottom of said plate, and a spring arranged upon said hinge-pin with end bearing, respectively, against said cover and said plate.

4. A can of the type specified comprising 80 the body of the can, a hood with funnel projection upstanding from the top front of the can body, a top rim to the can body lying back of said hood, a plate closing the back of said hood downward to the point of the top of said 85 rim, a cover to the can body closing against said rim, means for hinging the cover to said plate whereby when open it will occupy a position adjacent said plate, tension means for holding the cover in a normally closed position, and a clip mounting on 90 said hood for holding the cover in an open position.

5. A can of the type specified comprising 95 the body of the can having a handle, a hood with funnel projection extending from the 100 top front of the can body, a top rim to the can body lying back of said hood, a plate closing the back of said hood downward to the point of the top of said rim, a cover to the can body closing against said rim, means 105 for hinging the cover to said plate, a movable finger grip arranged within said handle operable by one grasping the handle, and means connecting said grip and said cover whereby said cover may be opened on moving 110 said grip.

6. A can of the type specified comprising 115 the body of the can having a handle, a hood with funnel projection extending from the top front of the can body, a top rim to the can body lying back of said hood, a plate closing the back of said hood downward to the point of the top of said rim, a cover to the can body closing against said rim, means for hinging the cover to said plate, a movable 120 finger grip arranged within said handle operable by one grasping the handle, means connecting said grip and said cover whereby said cover may be opened on moving said grip, and means for holding the cover normally 125 closed.

7. A can of the type specified comprising 130 the body of the can having a handle, a fixture on the top front of the can body, a cover arranged back of said fixture and hinged

thereto, a movable grip arranged within said handle and operable by one grasping the handle, a flexible connection between said grip and cover including a member fixed to the under side of said cover with extension forward beyond the hinge of the cover, and means for holding the cover normally closed.

8. A can of the type specified comprising the body of the can having a handle, a fixture on the top front of the can body, a cover arranged back of said fixture and hinged thereto, a lever arranged within said handle and operable by one grasping the handle, means for pivotally supporting the lower end of the lever, a guide for the top end of the lever, means for connecting the top end of the lever with said cover including a member fixed to said cover on the under side thereof with projection forward beyond the hinge of the cover, and means for holding the cover normally closed.
